(57) **CLAIM**

We claim the ornamental design for domestic and industrial robot, as shown.

DESCRIPTION

FIG. 1 is a front left perspective view thereof;

FIG. 2 is a front right perspective view thereof;

FIG. 3 is a front view thereof;

FIG. 4 is a rear view thereof;

FIG. 5 is a right side view thereof;

FIG. 6 is a right side view thereof with dispenser rotated;

FIG. 7 is a left side view thereof;

FIG. 8 is a left side view of thereof with arms rotated and knees bent;

FIG. 9 is a front perspective view thereof with arms bent and/or rotated;

FIG. 10 is a top view thereof with arms bent and/or rotated;

FIG. 11 is a bottom view thereof with arms bent and/or rotated; and,

FIG. 12 is a front left perspective view thereof with arms bent and/or rotated and body rotated.
